SEVERING APPARATUS

James A. Davis and Harold E. Hagerty, Williamsport, Pa., assignors to Armour and Company, Chicago, Ill., a corporation of Delaware

Filed Aug. 15, 1961, Ser. No. 131,542

8 Claims. (Cl. 83—67)

This invention relates generally to apparatus for severing portions from elongated strips of material, and it particularly relates to apparatus for severing desired portions from each of a series of elongated strips. For the purpose of simplicity, the invention herein described will relate to the rough cutting of shoe soles from leather strips.

In rough cutting shoe soles from leather pieces or strips, it has been the practice to manually feed an individual strip through a cutting machine and also to manually control each individual cut. Clearly, there would be a great saving in time, labor and expense if it were possible to consecutively and without interruption rough cut soles from leather strips, without the necessity of manually aligning and cutting soles from each strip. Further, a more uniform product would result if the manual operations were eliminated. Further, on each leather strip, both the leading portion and the trailing portion are ordinarily scrap pieces, since the trailing and leading edges are ordinarily not the desired shape for a sole. Therefore, apparatus not only should consecutively cut soles from an individual strip, but the apparatus should be adapted to process the scrap portions of each strip, so that a series of strips may be consecutively processed.

Therefore, it is a principal object of this invention to provide apparatus for consecutively severing portions from an elongated strip of material in uninterrupted operation.

It is also a principal object of this invention to provide apparatus for consecutively processing a series of elongated strips in uninterrupted operation.

It is a further object of this invention to provide apparatus for severing desired portions from each of a series of elongated strips.

It is still another object of this invention to provide apparatus for severing scrap portions, as well as desired portions, from a series of elongated strips, in a continuous uninterrupted operation.

It is a further object of the invention to provide an improved leather sole cutting apparatus.

Further purposes and objects of the present invention will appear as the specification proceeds.

The accompanying drawings illustrate one embodiment of the present invention, wherein:

FIG. 1 is a partially broken, side elevation view of the apparatus;

FIG. 2 is an enlarged, sectional view taken along line 2—2 of FIG 1;

FIG. 3 is an enlarged, detail view of mechanism used on the initial cut of an individual strip;

FIG. 4 is an enlarged top plan view of a leather strip and the apparatus used for starting and stopping the transfer mechanism and the severing mechanism; and,

FIG. 5 is a side elevation view of the embodiment shown in FIG. 4;

FIG. 6 is an enlarged sectional view of means 15 shown in FIG. 1 which is the mechanism for positioning the trailing portion of each of a series of strips for the final cut and for ejecting the trailing portion of each of a series of strips after the final cut;

FIG. 7 is a schematic diagram showing the switches.

2

In general, the apparatus includes a frame 10, transfer means, generally 11, means, generally 12, for positioning the leading edge of each strip, means, generally 13, for severing portions from each strip means, generally 14, for stopping transfer means 11 while actuating severing means 13, and means, generally 15, for positioning the trailing portion of each strip for the final cut.

The conveyor or transfer mechanism 11 includes a motor 16 and a gear unit 17 which are secured to frame 10. Sprocket 19 is fixed to gear unit shaft 20 and meshes with chain 21, which in turn meshes with sprocket 22 on shaft 23. Sprocket 22 turns contact wheel 24 which moves belt 25 so as to carry each strip towards means 12. Belt 25 is also positioned around contact wheel 26. Wheels 24 and 26 are rotatably mounted to frame 10. Sprocket 27 on shaft 20 meshes with chain 28, which in turn meshes with sprocket 29 and rotates sprocket 30, both sprockets 29 and 30 being fixed to shaft 31. Sprocket 30 meshes with chain 32, which in turn meshes with sprocket 33 on shaft 34.

Cutting or severing means 13 includes motor or drive means 35, which is secured to frame 10. Drive means 35 rotates drive shaft 37 through sprocket 38, chain 39 and sprocket 40. Gear 41 on shaft 37 meshes with gear 42 which in turn meshes with gear 43, gears 42 and 43 both being rotatably secured to frame 10. Tie rods 44 and 45 are eccentrically and rotatably attached to gears 42 and 43, respectively, in such a manner that knife 46 is down while knife 47 is raised. At their opposite ends, tie rods 44 and 45 are pivotally secured to knife supports 48 and 49. Knife supports 48 and 49 are pivotally fastened to frame 10. Knives 46 and 47 are adapted to contact cutting block 50 during each cutting operation. As shown in FIG. 5, the cut sole is adapted to drop from cutting block 50. Secured to shaft 37 is vane 51 which actuates vane switch 52.

Means 12 for positioning the leading portion 55 of a strip 56 includes a set of substantially horizontal rollers 57 and 58, having shafts 34 and 60 in substantially vertical alignment. As shown more clearly in FIG. 2, the lower set of rollers 57 includes roller 57a and 57b, and the upper set of rollers 58 includes rollers 58a, 58b, 58c and 58d. The upper set of rollers 58 is rotatably secured on shaft 60, shaft 60 being rotatable around roller support 64. Support 64 pivotally secured to frame 10 at 65. Support 64 is adapted to actuate switch 66 and a second switch 66a, which are secured to frame 10.

Means 15 for ejecting the trailing portion 67 of a strip 56 includes an air cylinder 70 pivotally mounted on support 71 of frame 10. The cylinder 70 is supplied with air through tubing 72. Piston shaft 73 of cylinder 70 is pivotally secured to linkage 74, which is also pivoted to the ejector shaft 75. Linkage 74 is pivotally mounted on frame 10 at pivot point 76. Spring member 77 moves shaft 73 away from cylinder 70, when there is no air pressure in the cylinder. Arm 75 is provided with a roller 78 at the front portion and is adapted to move on top of a strip 56. It is also adapted to push trailing portion 67 from cutting base or block 50.

Means 14 for stopping and starting the transfer mechanism 11 and for stopping and starting the severing mechanism 13 includes switches 81 and 80, as shown more clearly in FIG. 4. Switches 80 and 81 are adjustably mounted relative to support 82 which is secured to frame 10. Shaft 83 of adjusting wheel 84 is threadably secured in frame 82, on frame 10 and causes transverse motion of both switches 80 and 81. The switches 80 and 81 are individually adjusted relative to each other by means of screw members 85 and 86 which cause shafts 87 and 88 to slide within frame 82. Screws 85 and 86 are threadably secured in adjusting shaft support 89, which is fixed to shaft 97 of hand wheel 84. Hinged

members actuate switches 79 upon contact with appropriate portions of the strip 56.

Shown in FIG. 3 is a mechanism used on the first cut and includes shaft 90, which is slideable within sleeve 91, sleeve 91 being secured to frame 10. Arm 93 is secured to shaft 90 and is adapted to contact roller 94, which actuates switch 95, and a second switch 95a. Solenoid 96 is attached to frame 10 and maintains shaft 90 in the down position during the remainder of the cutting operations, until the end portion 67 of strip 56 passes through rollers 57 and 58.

In operation, a strip 56 is fed to the conveyor belt 25 and passes between pinch rolls 57 and 58, causing the upper rollers 58 to pivot around pivot point 65. This movement causes switch 66 to be actuated, starting a timer 66b which stops conveyor motor 16 after a given length of time. Also, a second switch 66c is actuated, cutting off the air supply to cylinder 70. This allows spring 77 to move shaft 73 away from cylinder 70, retracting arm 75 and roller 78 to a position on the upper side of a strip 56.

After the above mentioned timer reaches the end of its cycle, the drive means 16 for the conveyor is stopped and the drive motor 35 for the severing operation is started, causing knife or blade 46 to move downward for the first cut 100 on a strip 56. On its downward movement, support 48 contacts shaft 90, as shown in FIG. 3, causing switch 95 and a second switch 95a to be actuated. Switch 95 deactivates the circuit of the timer mentioned above. Switch 95 is maintained in the closed position since the second mentioned switch 95a is actuated, and energizes solenoid 96, which maintains shaft 90 in the down position. Knife 46 performs the first cut 100 upon contacting cutting base 50. Motor 35 continues to operate until the knife 46 is in the raised position. Motor 35 is stopped when the segmented section 92 of vane 51 passes through the slotted portion 52a of vane switch 52. This interrupts a magnetic flux which deenergizes vane switch 52, stopping motor 35 and starting motor 16.

Motor 16 moves belt 25 and thereby strip 56. When curved portion 101 of strip 56 contacts hinged member 79 of limit switch 81, the actuated circuit stops motor 16 and starts motor 35. Motor 35 moves blade 47 down for the second cut 102. After the cut is made, sole 103 drops from cutting block 50 and switch 81 is deenergized. However motor 35 continues to operate because of the previously described vane switch 52. After switch 52 is deenergized, motor 35 stops and motor 16 starts again moving the strip 56 forward until limit switch 81 is actuated by curved portion 104, stopping the conveyor drive means 16 and starting motor 35 again for the third cut.

The alternate starting and stopping of the strip 56 for each cutting operation is continued until the trailing or end portion 67 passes through rollers 57 and 58, causing the upper rollers 58 to pivot downward. When this happens, switch 66 and the second switch 66c are deactivated. Then, the air cylinder is activated by air pressure passing through a solenoid operated valve 66d, causing the arm 75 to move forward, pushing the strip 56 forward until a limit switch, 80 or 81, is actuated causing one of the knife blades 46 or 47 to move downward for a final cut as 105. Also, when one of the switches 80 or 81 is energized, the air cylinder 70 is deenergized and the arm 75 is retracted once again. After the cut has been made and the knife has returned to the parked position, the arm 75 moves forward again pushing the end portion 67 of strip 56 from the cutting block 50. Also switch 95 and the switch 95a that controls solenoid 96 are both deactivated, allowing shaft 90 to move upward, by means of spring 106. Also, the first cut timer circuit is set up again for another cycle of operations. Then the following strip to be processed passes between rollers 57 and

58 for processing. The operation can continue for an unlimited time, as long as strips are continuously moved to the apparatus.

In the foregoing specification, although there has been a detailed description of the apparatus for the purpose of illustrating a specific embodiment of the invention, it is understood that these details of construction may be varied widely by those skilled in the art without departing from the spirit and scope of the invention.

We claim:

1. An apparatus for severing adjacent portions of each of a series of elongated strips, comprising a frame, a unidirectional forwardly moving means comprising a cooperating conveyor and pressure rollers for forwardly moving each of a series of said strips, said means being in contact with said strips, a separate means, piston and spring operated, for positioning the trailing portion of each of a series of said strips for the final cut and for ejecting the trailing portion of each of a series of said strips after the final cut, severing means comprising a plurality of curved independently operated knives for performing first and second cuts on said series of strips, said moving means, severing means, and positioning and ejector means being secured to said frame, and means for intermittently starting and stopping said moving means, said severing means and said positioning and ejector means without manual assist.

2. An apparatus for severing portions from each of a series of elongated strips, comprising a frame, forwardly moving conveyor and roller means, secured to said frame, said roller means adapted for positioning the leading portion of each of said strips for an initial cut, severing means comprising a plurality of curved blades for cutting portions of each of a series of said strips, means for stopping said moving means while actuating said severing means and for starting said moving means while stopping said severing means, and means separate from the moving means for positioning the trailing portion of each of said strips for the final cut.

3. An apparatus for severing adjacent portions from elongated strips, comprising a frame, means for moving said strips, severing means comprising a plurality of knives for severing said adjacent portions from said strips, means for stopping said moving means while actuating said severing means for a cutting operation and for starting said moving means while stopping said severing means, means separate from said moving means for positioning the trailing portion of each elongated strip for the final cut and ejecting the trailing portion after the final cut.

4. An apparatus for severing portions from a series of elongated strips, comprising a frame, means for moving said strips forward, a severing means comprising a plurality of knives for cutting said strips, means separate from said moving means for positioning the trailing portion of each strip for a final cut and ejecting the trailing portion of each strip after the final cut, means for intermittently starting and stopping said moving means, said severing means and said positioning and ejector means without manual assist.

5. An apparatus for severing adjacent portions of strips from a series of said strips, comprising a frame, unidirectional forwardly moving means attached to said frame, a cutting base secured to said frame and aligned with said moving means, severing means comprising a plurality of curved knives independently operated and adapted to consecutively sever said portions upon contact with said cutting base, and means separate from said moving means for positioning the trailing portion of each of said strips on said cutting base for the final cut and for ejecting the trailing portion from said cutting base after the final cut.

6. An apparatus for severing adjacent portions from each of a series of elongated strips, comprising a frame, moving means secured to said frame comprising a conveyor and substantially horizontal rollers having their shafts in substantial vertical alignment, at least one of

said shafts being pivotally mounted relative to said frame, switch members for stopping said moving means, severing means secured to said frame and adapted with a plurality of blades to consecutively sever portions of said strips and means for positioning the trailing portion of said strip for a final cutting operation and for ejecting the trailing portion of said strip from said frame.

7. An apparatus for severing adjacent portions from each of a series of elongated strips, comprising a frame, a frame secured multi-bladed severing means, strip moving means secured to said frame comprising a conveyor and substantially horizontal rollers having their shafts substantially in vertical alignment, at least one of said shafts being pivotally mounted relative to said frame, switch members for stopping said conveyor means while actuating said severing means for cutting said strips, and means separate from said moving means for positioning the trailing portion of each strip and for ejecting the trailing portion of each strip after the final cut.

8. An apparatus for severing adjacent portions of each of a series of elongated strips, including a frame, moving means, including a conveyor and pressure rollers, said pressure rollers being aligned with said conveyor and secured to said frame for positioning the leading portion of each of a series of said strips for the initial cut, severing means including a plurality of knife blades alternately actuated for consecutively severing portions of each of said strips, said severing means being secured to said frame, frame secured spring and piston operated position-

5 ing and ejector means for positioning the trailing portion of each of a series of said strips for the final cut after each strip passes through said pressure rollers and for ejecting the trailing portion of each strip after the final cut, means for stopping said moving means while actuating said severing means and means for stopping said severing means while actuating said positioning and ejector means, said positioning and ejector means being actuated by the passing of said trailing edge from between 10 said pressure rollers after a series of cuts on said strip and before the final cut on said strip.
